ATTORNEY

UNITED STATES PATENT OFFICE.

STERLING H. CAMPBELL, OF ST. LOUIS, MISSOURI.

BRACKET FOR UNCOUPLING DEVICES.

1,358,363.

Specification of Letters Patent.

Patented Nov. 9, 1920.

Original application filed December 13, 1919, Serial No. 344,553. Divided and this application filed March 24, 1920. Serial No. 368,278.

To all whom it may concern:

Be it known that I, STERLING H. CAMPBELL, a citizen of the United States of America, residing at the city of St. Louis, State of Missouri, United States of America, have invented a certain new and useful Bracket for Uncoupling Devices, of which the following is such a full, clear, and exact description as will enable anyone skilled in the art to which it appertains to make and use the same, reference being had to the accompanying drawings, forming part of this specification.

My invention relates to a bracket for uncoupling devices and is more particularly adapted for use in connection with uncoupling devices such as that shown and described in my prior application No. 344,553 of December 13, 1919, of which the present application is a division. It may, however, be used in connection with other forms of uncoupling device.

In the accompanying drawings which illustrate one form of bracket made in accordance with my invention, Figure 1 is a top plan view, Fig. 2 is a side elevation, and Fig. 3 is a front elevation.

5 indicates a base plate which may be secured to the end of the car by bolts or rivets 6 passing through openings 7 in the said base plate. 9 is a vertical slot formed between a forwardly projecting V-shaped portion 10 of the base 5 and an opposing wall 11. This vertical slot 9 is adapted to receive the operating lever 12 of the uncoupling device. This operating lever 12 rests upon a curved bearing 14 forming the bottom of the slot 9. 15 is a locking pin adapted to be swung across the top of the 40 vertical slot to secure the lever 12 in position and provided with a downwardly projecting bearing portion 16 terminating in a head 17. This bearing portion 16 is held between a pair of malleable lugs 18 which 45 are adapted to be bent around it from the position shown in dotted lines in Fig. 1 to that shown in full lines, thus permanently securing the locking pin in position so that it cannot become detached from the device. 50 The pin 15 is provided with a portion 19 extending at right angles to the body of the pin and adapted to project through an opening 20 in a lug 21, when the pin is in locking position as shown in Figs. 2 and 3.

55 The lug 21 is formed integral with the

wall 11 and preferably forms a continuation of a strengthening flange 22. The end of the part 19 of the pin is provided with a slot 23 so that after the locking pin is moved into position to hold the lever 12 the end of the part 19 may be spread to prevent its withdrawal from the opening 21.

It will be evident that my device is of the simplest possible construction consisting of two parts and as these parts are permanently secured together it will be impossible for the device to get out of order by the loss of some of the parts as is usual in brackets heretofore in use for this purpose.

Having fully described my invention, what I claim as new and desire to secure by Letters Patent of the United States is:

1. A bracket for an uncoupling device having an integral seat for an operating lever and a passage for receiving the lever 75 coöperating with said seat and permitting vertical movement of said lever, of locking means for retaining said lever in operative relation to said seat.

2. A bracket for uncoupling devices having a passage open at the top and adapted to receive an operating lever, and a movable member permanently carried by said bracket and adapted to close the top of said passage to prevent the removal of the operating lever.

3. A bracket for uncoupling devices having an integral seat for an operating lever and a passage for receiving the lever coöperating with said seat and permitting vertical movement of said lever, of a pivoted member permanently carried by said bracket and adapted to retain said lever in operative relation to said seat.

4. A bracket for uncoupling devices provided with an integral seat adapted to receive an uncoupling lever, and means carried by said bracket and moving in a plane substantially parallel to the length of the operating lever for retaining said lever in 100 position.

5. A bracket for uncoupling devices having a passage open at the top and adapted to receive an operating lever, and a pivoted member permanently carried by said bracket 105 and adapted to be swung across the top of said passage to prevent the removal of the operating lever.

6. A bracket for uncoupling devices having a slot adapted to receive an operating 110

lever, said slot being provided with a curved bottom and an open top, and a movable member permanently carried by said bracket and adapted to close the top of said passage to prevent the removal of the operating lever.

7. A bracket for uncoupling devices having a slot adapted to receive an operating lever, said slot being provided with a curved bottom and an open top, and a pivoted member permanently carried by said bracket and adapted to close the top of said passage to prevent the removal of the operating lever.

8. A bracket for uncoupling devices having a slot adapted to receive an operating lever, said slot being provided with a curved bottom and an open top, a movable member permanently carried by said bracket and adapted to close the top of said passage to prevent the removal of the operating lever, and integral locking means carried by said movable member.

In testimony whereof, I have hereunto set my hand and affixed my seal.

STERLING H. CAMPBELL. [L. S.]
